CLAIM

The ornamental design for a teddy bear plush toy, as shown and described.

DESCRIPTION

FIG. 1 is a front perspective view of a teddy bear plush toy; FIG. 2 is a front view of the teddy bear plush toy of FIG. 1 showing transparent chamber with dosed lid thereof; FIG. 3 is a front view of the teddy bear plush toy of FIG. 1 showing transparent chamber with open lid thereof; FIG. 4 is a rear view of the teddy bear plush toy of FIG. 1 thereof;

FIG. 5 is a right side view of the teddy bear plush toy of FIG. 1 thereof;

FIG. 6 is a left side view of the teddy bear plush toy of FIG. 1 thereof;

FIG. 7 is a top view of the teddy bear plush toy of FIG. 1 thereof; and,

FIG. 8 is a bottom view of the teddy bear plush toy of FIG. 1 thereof.

The broken lines in FIGS. 1-8 are for the purpose of showing portions of the teddy bear plush toy that form no part of the claimed design.

1 Claim, 8 Drawing Sheets
